(57) **CLAIM**

The ornamental design for a compression latch, as shown and described.

DESCRIPTION

FIG. 1 is a perspective view of an embodiment of a compression latch embodying our new design with the compression latch in the latched configuration and the handle folded down;

FIG. 2 is a right side elevational view thereof, the left side elevational view being a mirror image of the right side; FIG. 3 is a front elevational view thereof; FIG. 4 is a rear elevational view thereof; FIG. 5 is a top plan view thereof; FIG. 6 is a bottom plan view thereof; FIG. 7 is a perspective view of the compression latch of FIGS. 1-6, showing the handle raised up; FIG. 8 is a right side elevational view of the compression latch of FIG. 7, the left side elevational view being a mirror image of the right side; FIG. 9 is a front elevational view of the compression latch of FIG. 7; FIG. 10 is a rear elevational view of the compression latch of FIG. 7; FIG. 11 is a top plan view of the compression latch of FIG. 7; FIG. 12 is a bottom plan view of the compression latch of FIG. 7; FIG. 13 is a perspective view of the compression latch of FIGS. 7-12, showing the handle rotated 180°; FIG. 14 is a right side elevational view of the compression latch of FIG. 13, the left side elevational view being a mirror image of the right side; FIG. 15 is a front elevational view of the compression latch of FIG. 13; FIG. 16 is a rear elevational view of the compression latch of FIG. 13; FIG. 17 is a top plan view of the compression latch of FIG. 13; FIG. 18 is a bottom plan view of the compression latch of FIG. 13; FIG. 19 is a perspective view of the compression latch of FIGS. 13-18, showing the handle folded down; FIG. 20 is a right side elevational view of the compression latch of FIG. 19, the left side elevational view being a mirror image of the right side; FIG. 21 is a front elevational view of the compression latch of FIG. 19; FIG. 22 is a rear elevational view of the compression latch of FIG. 19; FIG. 23 is a top plan view of the compression latch of FIG. 19; and, FIG. 24 is a bottom plan view of the compression latch of FIG. 19;
